TUMBLER OR SIMILAR ARTICLE

Frederick J. Pool, Glenview, Ill., assignor to Prodare
Company, Village of Wilmette, Ill., a partnership

Filed Feb. 12, 1965, Ser. No. 33,803

Term of patent 14 years

(Cl. D44—9)

FIG. 1

FIG. 3

FIG. 1 is a top plan view of a tumbler or similar article embodying my new design;

FIG. 2 is a side elevational view, and

FIG. 3 is a bottom view.

I claim:

The ornamental design for a tumbler or similar article, substantially as shown.
